UNITED STATES PATENT OFFICE

102,399

DESIGN FOR A TWIN FACE DIRECTIONAL SIGNAL

Samuel J. Shaw, Jr., Nyack, N. Y.

Application May 8, 1936, Serial No. 62,542

Term of patent 7 years

To all whom it may concern:

Be it known that, Samuel J. Shaw, Jr., a citizen of the United States of America, residing at Nyack, in the county of Rockland and State of New York, has invented a new, original, and ornamental Design for Twin Face Directional Signal of which the following is a specification; reference being had to the accompanying drawing, forming part thereof.

Figure 1 is a front elevational view of a twin face directional signal, showing my new design; and

Figure 2 is side elevational view thereof.

I claim:

The ornamental design for a twin face directional signal as shown.

SAMUEL J. SHAW, JR.
